UNITED STATES PATENT OFFICE.

GEORGE W. WOODWARD, OF NEW YORK, N. Y., ASSIGNOR TO WOLCOTT A. HULL AND THE ANSONIA BRASS AND COPPER COMPANY, OF SAME PLACE.

DESIGN FOR A LAMP-RESERVOIR.

SPECIFICATION forming part of Design No. 15,781, dated February 3, 1885.

Application filed August 15, 1884. Term of patent 7 years.

To all whom it may concern:

Be it known that I, GEORGE W. WOODWARD, of New York, in the county and State of New York, have originated a new and useful Design for Lamp-Reservoirs, of which the following is a specification.

My design relates to lamp-reservoirs.

In the accompanying drawings, Figure 1 is a perspective view of a lamp-reservoir embodying my design, and Fig. 2 is a sectional elevation thereof.

Similar letters of reference designate corresponding parts in both the figures.

A designates the body of the reservoir. As shown, it is bowl-shaped, its external surface being continuously convexed.

B designates the bottom of the reservoir. Above the bottom the reservoir is curved inwardly and then outwardly, forming a groove-like portion, b. The groove-like portion is surmounted by an outwardly-projecting portion or shoulder, c. Above the shoulder c is a flaring portion, d. Above the portion d the periphery of the body is preferably ornamented with diamond-shaped projections a. The top C of the reservoir I have shown as

having near the outer edge a rim, e, and inward of the rim e a raised portion, f. The raised portion f is rounded. Inward of the raised portion f the top curves downward and then upward, forming a hollowed groove-like portion, g. The inner edges of the groove-like portion g terminate in a raised portion, h, which is flattened upon the top and is somewhat higher than the portion f. Inward of the portion h is another raised portion, i. The portion i is surmounted by a rim, j, to which may be secured a burner. A neck-like portion, k, extends outwardly from the portion h. Said neck-like portion is surmounted by a ring, l, having a thumb-piece, m.

What I claim as my design, and desire to secure by Letters Patent, is—

In a design for a lamp-reservoir, the body A, having the diamond-shaped ornaments a, the flaring portion d, and the rim e, and the bottom B, substantially as shown and described.

GEORGE W. WOODWARD.
